UNITED STATES PATENT OFFICE

93,049

DESIGN FOR AN EXTENSIBLE GRILLE

August L. Schon, Dallas, Tex.

Application March 10, 1934, Serial No. 51,006

Term of patent 14 years

To all whom it may concern:

Be it known that I, AUGUST L. SCHON, a subject of Luxemburg, residing in Dallas, in the county of Dallas and State of Texas, United States of America, have invented a new, original, and ornamental Design for an Extensible Grille, of which the following is a specification, reference being had to the accompanying drawing, forming a part thereof:

The figure is a plan view of a grille showing my new design, which is extensible by loosely riveting together crossbar members to permit a lateral extension.

I claim:

The ornamental design for an extensible grille as shown and described.

AUGUST L. SCHON.
